UNITED STATES PATENT OFFICE.

HENRY A. MATTHEWS, OF WATERBURY, CONNECTICUT.

FOOT-BAR FOR STOVES.

SPECIFICATION forming part of Letters Patent No. 312,877, dated February 24, 1885.

Application filed January 2, 1885. (No model.)

To all whom it may concern:

Be it known that I, HENRY A. MATTHEWS, of Waterbury, in the county of New Haven and State of Connecticut, have invented a new 5 Improvement in Foot-Bars for Stoves; and I do hereby declare the following, when taken in connection with accompanying drawings, and the letters of reference marked thereon, to be a full, clear, and exact description of the same, 10 and which said drawings constitute part of this specification, and represent, in—

Figure 1, a side view, one end being in longitudinal central section; Fig. 2, a transverse section enlarged; Fig. 3, a modification 15 showing the cap formed as a part of the tip.

This invention relates to an improvement in the construction of bars such as applied to stoves, and upon which a person may place the feet as a rest. These bars are made ornamental, and in the better class of stoves the surface is electroplated, usually with nickel. These bars are made in the better class by employing a drawn metal tube of sufficient strength to sustain the feet, the ends provided 20 with an ornamental tip introduced into the ends of the tube. They are sometimes filled with wood, or may be with a metal bar, to give them greater strength. The tubes are usually of brass, so that they may be polished and 25 left presenting the brass surface, or electro-plated. These tubes are expensive, and add materially to the cost of the stove. If the bars be made of iron, say as an iron rod, the surface requires to be finished and polished, 30 making the expense very nearly as much as the finer metal tube. In the employment of the tube, if an ornamentation of the surface is desirable, the range of ornamentation is extremely limited, as it must be of a character 35 which can be made in drawing the tube or in the lathe, as by spinning or turning.

The object of my invention is to cheapen the cost of manufacture of the bar to a very considerable extent, and at the same time permit 45 a great variety of ornamentation upon the surface; and it consists in a hard metal tubular body combined with a thin sheet-metal jacket folded around the body, and a cap applied to each end to inclose the end of the jacket, 50 et, as more fully hereinafter described.

The tubular body A may be made from stout

sheet-iron simply bent into tubular shape, bringing its two edges to abut together, as at a, there being no occasion for a brazed or welded joint. The jacket or outer surface is made 55 from a strip of sheet metal in length corresponding to the length of the body—that is, the bar required—and in width to little more than surround the body. This covering is folded around the body, and should be so that 60 the edges will overlap, as at b, Fig. 2. At each end a cap, d, is applied, its flange extending onto the outer covering, as seen in Fig. 1. Through each of these caps is a central hole, e. Longitudinally through the bar, and extending 65 through the hole in each cap, is a rod, C. The holes in the cap locate this rod in a central or concentric position. Its ends are screw-threaded, as at f, and onto the projecting end of the rod the tips D are screwed, as seen in 70 Fig. 1.

By thus making the body from a strip of metal bent into tubular shape the cheapest possible body is produced.

By making the covering from sheet metal I 75 am enabled to employ rolled metal, having its surface ornamented in the process of rolling, and thereby produce a great variety of ornamentation, and with no additional cost, as the cost of rolling an ornamental surface is no more 80 than that of a plain surface.

The surface of the covering may be electro-plated or finished in the sheet, so that no labor is required upon it other than simply wrapping it around the body. 85

The caps at the end securely hold the covering to the body at the ends, and there is no liability to separate at other points. The joint, it will be understood, is hidden by being placed upon the back or under surface, where it will 90 not appear to the eye. It will be seen, therefore, that this construction enables me to produce a highly ornamental bar at a cost very much less than even the plainest bars as heretofore produced. 95

The cap may be made as a part of the tip, as seen in Fig. 3, the flange embracing the covering, the same as in the separate cap; yet I prefer to apply the cap to the bar independent of the tip. 100

While this bar is designed with special reference to use upon stoves, its construction may

be applied to similar metal bars for other purposes, as for window-curtain bars, for illustration.

I claim—

- 5 1. The herein-described metal bar, consisting of the tubular body A, and the sheet-metal covering B, folded around the said body, combined with a cap at the ends to inclose the end of the covering, the ends terminating in a tip, 10 D, substantially as described.
- 10 2. The combination of the tubular body A,

the sheet-metal covering B, folded around said body, the cap d, applied at the ends of the bar, and so as to inclose the covering at the ends, the rod C, longitudinally through said bar and concentrically through the caps, and tips D applied to the ends of the said rods and against the said caps, substantially as described. 15

HENRY A. MATTHEWS.
